UNITED STATES PATENT OFFICE.

HARRY J. MEISEL, OF BUTTE, MONTANA.

AUTOMATIC SAFETY-DOOR FOR MINES.

1,322,923.

Specification of Letters Patent. Patented Nov. 25, 1919.

Application filed October 16, 1917. Serial No. 196,891.

To all whom it may concern:

Be it known that I, HARRY J. MEISEL, a citizen of the United States of America, residing at Butte, in the county of Silver Bow 5 and State of Montana, have invented certain new and useful Improvements in Automatic Safety-Doors for Mines, of which the following is a specification.

This invention relates to certain new and 10 useful Improvements in automatic safety doors for mines.

The primary object of the invention is the provision of safety doors for mines adapted for automatically closing upon a break, 15 either accidentally or intentionally, in an electrical circuit of the safety system installed in the mine.

A further object of the device is the provision of a double door adapted for closing 20 an entry or a passage through a mine, such as a level thereof, in the event of a fire or other exigency when it becomes necessary to cut off communication between different portions of the mine, the device being unaffected by any mine drafts and being electrically controlled wherever the occasion requires.

A still further object of the invention is the provision of a safety mine door construction adapted for normal maintainance 30 in its open arrangement by means of a closed electrical circuit, the releasing of the device for automatically closing the doors being affected by means of electrical switches 35 and fuses located either in the mine or above the surface of the earth, while the device is automatically operated upon any break in the electrical circuit such as that caused by the burning of the wires in the event of a 40 fire in the mine either destroying or short circuiting the electrical circuit of the system.

With these general objects in view and others that will appear as the nature of the 45 invention is better understood, the same consists in the novel construction, combination and arrangement of parts hereinafter more fully described, illustrated in the accompanying drawings, and pointed out in 50 the appended claims.

In the drawings forming a part of this application, and in which like designating characters refer to corresponding parts throughout the several views.

55 Figure 1 is a vertical sectional view through a mine shaft and lateral level,

mainly diagrammatic, illustrating the electrical system of the device,

Fig. 2 is a horizontal sectional view taken through a portion of the mine provided 60 with the device the latter being shown in its open arrangement and parts being broken away,

Fig. 3 is an elevational view of one end of the device,

Fig. 4 is a side elevation of a portion thereof with one abutment shown in vertical section,

Fig. 5 is an enlarged top plan detail view of a portion of the device slightly enlarged 70 illustrating the electrical latch mechanism, and

Figs. 6 and 7 are elevational views taken from different sides thereof.

It being understood that the device may 75 be employed in connection with any form of mine and either in an entry, drift, passage or shaft thereof, the same is herein illustrated in connection with a first level or entry 10 laterally constructed with respect to 80 the vertical main shaft 11 of the mine.

Wherever it is desired to position doors for cutting off communication with different parts of the mine, oppsite abutments 12 and 13 are constructed of fire-proof material 85 such as cement, the same being arranged against the opposite walls 14 of the mine from the roof 15 to the bottom or floor 16, of the said level or entry 10.

Similar doors 17 and 18 are arranged at 90 opposite sides of the abutments 12 and 13 mounted by means of hinges 19 to door frames 20 of angle iron formation. The said doors 17 and 18 are normally arranged in substantial alinement with each other 95 when the doors are open and swing inwardly toward the abutments 12 and 13 and toward each other when moving to their closed positions within the door frames 20. The said doors taken together form a single closing 100 unit.

An angular shield 21 is arranged at the corresponding side of each frame 20 adapted for the accommodation of a closing weight 22 for the adjacent door, operatively 105 connected to an arm 23 attached to the upper outer corner of each door 17 by means of a metal cable or similar flexible connector 24 which passes over a swivelly mounted pulley 25 carried by the abutment 13 above 110 each of the shields or guards 21.

An arm 26 formed of angle iron projects

from the abutment 12 perpendicularly with respect to the top of the adjacent door frame 20 and is preferably connected thereto by means of braces 27. A solenoid 28 is mounted by means of a bracket 29 upon the free end of each arm 26 as at 30 where the upper flange of the arm is broken away. The core 31 of the solenoid 28 is pivotally connected to a latch 32 pivoted upon a finger 33 of the arm 26 and having a hooked free end 34 adapted for seating reception within a keeper socket or slot 35 in the adjacently positioned flange 36 of the door 17 when the latter is in its open arrangement and the core 31 is retracted with the electrical circuit of the solenoid unbroken.

From this description of the device it will readily be understood that upon elevating the latches 32, the doors 16 will be released and the weights 22 will automatically close the oppositely arranged doors within the casing 20 forming a fire-proof door construction. The rails 37 of the mine railway pass through the door casings 20 and are preferably arranged with filler blocks 38 of cement or other fire-proof material arranged between the rails 37 and the abutments 12 and 13 at opposite points inwardly of the door frames 20. The floor 16 of the mine is arranged above the bottom portion 40 of each of the door frames 20, while the closing of the doors 17 above the tracks 37 and adjacent the blocks 38 forms a substantially fire and gas tight joint at the bottoms of the doors when closed sufficient for preventing the passing of flames between the space intermediate the said doors. Circuit wires 41 are provided for the solenoids 28 arranged for passing through a conduit 42 in the abutment 12 and preferably arranged with a single throw switch 43 in the circuit wires leading to each of the solenoids, while a single throw short circuit switch 44 may be arranged in each level or entry of the mine for controlling all of the doors arranged therein.

Main line wires 45 supply current to the circuit wires 41 and extend from a source of electrical supply outside of the mine to points through the shaft 11. A double pole single throw switch 46 is arranged above the ground in the main line wires 45 while a fuse 47 is also arranged in each of the main line wires. A handle 49 may be provided for each of the doors 17 while it will be understood that the door frames 20 are anchored as at 50 to the abutment 12. Pipes 51 are arranged in the usual manner through the mine for conducting air and water and for any purposes desired, it being understood that the space between the door casings 20 and the roof 15 of the mine is suitably filled in by metal plates such as 52 or cement work if desired.

With the system arranged with the doors

17 normally retained open by the latches 32 as herein indicated, the switches 43 and 46 will be closed and the thermal plugs 47 will be mounted in the fuse block 48. In the event of a fire occurring at any point 70 in the mine and burning any of the wires 41 or 45, sufficiently to sever one of the wires or short circuit the system, the solenoids 28 will be deenergized and the cores 31 being released will drop of their own weight 75 thereby releasing the latches 32 from the slots 35 of the doors 17 and permitting the weights 22 to automatically close the said doors simultaneously. When it is desired to close all of the doors in the mine, 80 the switch 46 may be opened thereby breaking the electrical connection for all of the solenoids 28 and releasing all of the doors. The switch 44 controls all of the doors upon the level or entry at the mouth of which 85 said switch is arranged and upon closing the switch 44 the circuit wires 41 for the solenoids within that level will be disconnected from the source of supply by being short circuited resulting in the closing of 90 the doors of the level.

It will be also noted that a short circuit occurring either intentionally or accidentally within the wires of the system, will result in blowing the fuses 47 and disconnecting the main line wires 45 from the mine resulting the same as the opening of the switch 46.

It will be seen that a serviceable safety arrangement for mines is provided being 100 a protection against fire for automatically cutting off any passages in which a fire may occur as well as arranging a system by which all of the levels of a mine may be cut off from the main shaft from a station 105 above the ground whenever it is desired by the mine owner.

While the form of the invention herein shown and described is what is believed to be the preferred embodiment thereof, it is 110 nevertheless to be understood that various forms, modifications and arrangements of the parts may be made without departing from the spirit and scope of the invention as claimed.

What I claim as new is:—

A safety device for mines comprising relatively spaced oppositely arranged abutments located in a mine passage, door frames secured to the opposite sides of the 120 abutments, a door hinged to each frame for horizontal swinging movement toward and away from each other, an angular shield arranged at the corresponding side of each door frame remote from the end to which 125 the door is hinged, a closing weight movable in each shield, a fixed arm outwardly projecting from each door frame, bracing means connecting the arm to the door frame, upwardly and outwardly projecting attach- 130

ing means carried by the upper outer corner of the free end of each door, a cable connected to the free end of each attaching means and to the weight in each shield

5 whereby the doors may be automatically closed, and an electrically operated latch mechanism carried by the outer end of each

arm and adapted for engagement with the upper edge of the free end of each door for normally holding the doors in open position. 10

In testimony whereof I affix my signature.

HARRY J. MEISEL.
